UNITED STATES PATENT OFFICE.

CHARLES WALES, OF NEW HAVEN, CONNECTICUT, ASSIGNOR TO THE WHITE ADDING MACHINE COMPANY, OF NEW HAVEN, CONNECTICUT, A CORPORATION OF CONNECTICUT.

PRINTING MECHANISM.

1,232,738.

Specification of Letters Patent. Patented July 10, 1917.

Application filed April 3, 1914. Serial No. 829,197.

To all whom it may concern:

Be it known that I, CHARLES WALES, a citizen of the United States, residing at New Haven, county of New Haven, State of Connecticut, have invented certain new and useful Improvements in Printing Mechanism, of which the following is a full, clear, and exact description.

My invention relates to improvements in printing mechanism for computing machines and has for its object to produce a printing mechanism in which the hammers act upon any one of a series of type members, the hammer and type members being so guided 10 that at the moment of impact, the hammer will strike the type member squarely. It further has for its object to provide means whereby the ready re-coil of the hammer after impact is permitted.

20 The following is a description of an embodiment of my invention, reference being had to the accompanying drawings, in which,

Figure 1 shows the printing mechanism in 25 side elevation.

Fig. 1^a is a detail (on double scale) of one of the springs when the parts are in the positions shown in Fig. 1.

Fig. 2 is a longitudinal section of the 30 apparatus on an enlarged scale, showing one of the hammers in retracted or cocked position.

Fig. 3 is a sectional view showing details of the links for lifting the type carrier and 35 their relation to hammer-lock lifters.

Fig. 4 is a front view of the guide plate for the type members and hammers.

Fig. 5 is a horizontal section on the line 5—5 (Fig. 1) showing details of certain 40 parts, other parts being omitted.

Fig. 6 is another detail on the line 6—6 (Fig. 1).

Referring more particularly to the drawings, A is a metal frame supporting a platen 45 A', a channeled plate B and a shaft D¹⁷ for the levers D¹⁸ which position the type members. Carried by the plate B there are two side members C of the hammer mechanism. In each of the channels of the member B is 50 a guide rod D carrying at its upper end type members D², whose rear typefaced ends D³ are adapted to strike against the platen A' and whose front ends are to be hit by the hammers. The guide rods D are held within 55 the channels B' in the plate B by a retaining

plate B². The type members are surrounded by housings D⁴ which housings are respectively secured to their guide rods D. The type members are provided with slight vertical extensions D⁷, which engage the front 60 surface of the housing so as to limit the forward movement of the type members within the housing. The type members are provided with recesses in which are located helical springs D⁸ which at their rear ends 65 bear against the rods D so as to tend to move the type members away from the platen.

Upon a shaft F' carried by the members C, is loosely mounted a series of hammers F, struck from sheet metal and having no projecting hubs. Upon said shaft F' and separating the hammers, is a series of spacing rings F⁴. The hammers are provided with forwardly projecting lever arms F⁶, each having a notch F⁶, with which engages a restraining bail F⁷, forming a part of a lever 70 loosely mounted upon the connecting bolt C⁵. Upon said shaft F' are also carried two bell cranks F¹⁰ rigidly connected thereto and between the lower ends of which is a cross bar 80 F⁸, adapted to engage with the lever arms F⁶. Connected to the upper end of one of the bell cranks F¹⁰ is a forwardly extending connecting rod F⁹ having a slot in its forward end, which engages a stud upon the upper 85 end of the lever F¹¹, carrying the bail F⁷. Upon the cross bolt F¹² is shown one of a series of locking triggers, F¹³ each having a tooth F¹⁴ adapted to engage the projection on F¹⁵ upon the shank of the corresponding 90 hammer F. These locking triggers have the usual over-lapping fingers F¹⁶, each engaged by the trigger to the left, by which movement is transmitted from one of said locks to the next to the right. Springs F¹⁸ connect 95 the rear ends of the triggers F¹³ with a suitable abutment F¹⁹ in this case on the front portion of a guide plate F²⁰ hereafter described at length, and tend to keep the teeth F¹⁴ of the triggers in depressed position. 100 Upon a cross rod F²² to the rear of the cross rod F¹² is a series of hammer lock lifters F²¹, the rear ends of which tend to rise by reason of the springs F²³ connected thereto and to the cross plate F²⁴ carried by the 105 frames C. To the front end of the lever arms F⁶ of the hammers are connected one end of springs F²⁵, the other end being connected to plate F²⁶, carried by sliding members F²⁷, which ride upon the cross bars F⁸, 110

their upper ends being guided between the cross rod C⁴ and the front ends of the guide plate F²⁰. This guide plate F²⁰ is shown in detail in Fig. 4 and is provided with lateral projections F²⁹ by which it is secured to the lateral plates C. This guide plate F²⁰ is provided with slots F³⁰ for the front ends of the type members and with slots F³¹ for the stems or shanks of the hammers F. The slots F³¹ constitute guides for the hammers at points remote from the shaft on which the hammers are mounted. The lower ends of the slots F³⁰ are slightly enlarged so as to make it easier for the ends of the type members to enter therein. The slots F³⁰ are directly in line with the slots F³¹ and are separated therefrom by dividing portions F³² so as to increase the rigidity of the central portion of the plate. The slots F³⁰ are slightly wider than the slots F³¹ to accommodate the ends of the type members which are slightly wider than the thickness of the rear end of the hammer F.

The lifting links D⁹ are provided with projections D²⁵, which engage the rear ends of the hammer lock releasers F²¹ and hold them out of operation when the lifting links D⁹ are in depressed position.

The guide plate F²⁰ with its slots F³⁰ positions the front ends of the type members at the time the hammer F makes impact therewith and the slots F³¹ guide the hammers F at points remote from the shaft on which they are mounted, so that their striking points make a true blow upon the front ends of the type members, thus insuring accuracy in the blow of the hammer, which is of great importance in producing a proper impression upon the paper carried by the platen.

The spring F²⁵ is shown in Fig. 1 in the position it assumes, while the hammer is in engagement with one of its type members. The spring 25 is of such length that when the hammer is in this position, its active coils bear against each other as shown in Fig. 1^a so that it is slack and no longer exerts any pulling effort, the total length of the contracted spring being such as to entirely relieve the strain thereon at the instant the hammer causes the type member to strike the platen. This permits the instantaneous rebound of the hammer from the platen after the stroke has been made, thus insuring the rebound of the hammer without the use of additional devices as expedients.

The rings F⁴ and the hammers fit so closely together upon the shaft F' as to provide for the movement of oil by capillary action between the adjacent faces of these parts and along the shaft F' from one end of the series of bearings and rings to the other end of said series so that when oil is applied to one portion of said series, the oil

will travel through the remainder of said series, with the result that when oil is consumed faster at one portion of said series (the portion most used) the oil will travel from the other portions into the portion where there is the least oil.

The confining of the upper portions of the hammer stems in the slots insures an accurate movement of the hammer during its stroke, notwithstanding lack of precision in the fitting of the hammer bearing about the rock shaft F' and with reference to the spacing rings F⁴. The accuracy thus obtained permits the use of sheet metal hammers which do not have projecting hubs and the forming of these parts by ordinary machine methods and thereafter assembling them without fitting, saving the labor and expense in manufacture and leading to durability after manufacture.

The confining of the type stems in the slots F³⁰ leads to the precise positioning and movement of the type. This avoids the lateral turning of the type bar housing and the type bars on account of looseness in the fitting and the guiding of the type and the hammer in the manner described, insures the bringing of the type stem and hammer into the same plane at the moment of impact, so that the hammer stroke is made accurate and effective, there being the least possible side thrusts from the blow.

The general operation of the mechanism is well understood by those skilled in the art. The levers D¹⁶ are operated so as to raise the links D⁹ and position the type bars D² according to the number to be set up, the hammers having been retracted by the downward movement of the bar F⁸, brought about by the movement of the shaft F'. After the type bars have been set up, the shaft F' is rotated in a counter clockwise direction. (Fig. 1) and raising of the bar F⁸ puts the springs F²⁵ under the tension, the bar F⁸ moving upward so as to be free from the lower ends of the hammer levers which are held restrained by the bail F⁷ actuated by the spring F¹¹ and in the notch F⁶. When the springs F²⁵ have been placed under sufficient tension, the forward end of the link F⁹ withdraws the bail F⁷ releasing the hammers, whose locking triggers have been withdrawn. These locking triggers are controlled in part by the lugs D²⁵ upon the links D⁹, as will be well understood. When any hammer lock is released, all hammer-locks to the right thereof will also be released, each hammer-lock acting upon the tail piece F¹⁶ of the hammer lock to its right to withdraw it from holding position.

What I claim is:

1. In a mechanism of the nature described, a combination with a platen of vertically movable type-supporting rods, a plurality of type members borne by each of said type-

supporting rods, a slotted stationary guide plate each slot receiving the ends of a plurality of said type members, a shaft, hammers loosely mounted upon said shaft, and 5 means for setting and firing said hammers, the ends of said type members being movable both vertically and horizontally relatively to said guide plate.

2. In a mechanism of the nature described, 10 a combination with a platen of type-supporting rods, type members borne by said type-supporting rods, a guide plate having slots receiving the ends of said type members, a shaft, hammers loosely mounted upon 15 said shaft, and means for setting and firing said hammers, the lower portions of said slots being expanded, said type members being adapted to leave and enter said slots at their lower ends.

20 3. In a mechanism of the nature described, a combination of a platen, type-supporting rods, type members carried by said type-supporting rods, a guide plate having a rear series of slots guiding said type members, and 25 a front series of slots, the slots of each series conforming in number to the number of type-supporting rods, a shaft, hammers loosely surrounding said shaft and extending through the front row of said slots and 30 means for setting and firing said hammers.

4. In a mechanism of the nature described, 35 the combination of a platen, a guide plate having a forwardly extending portion provided with a forward series of slots and an upwardly extending portion having a rear series of slots which extend somewhat into said forwardly extending portion and are in alinement with the slots within said forwardly extending portion, vertically movable 40 type rods, type members carried thereby and positioned by the rear slots in the vertical portion, and oscillating hammers guided by the slots in the forwardly extending portion.

45 5. In a mechanism of the nature described, the combination of a platen, a guide plate having a vertically extending portion and also forwardly extending top and bottom

portions and parallel slots beginning in said bottom portion and ending in said upper 50 portion, vertically movable type-carrying rods, a vertical series of type members carried thereby and adapted to pass into and out of said slots, and hammers for striking said type members. 55

6. In a mechanism of the nature described, the combination of a platen, a guide plate having a forwardly extending portion provided with front slots and an upwardly extending portion having rear slots which extend somewhat into said forwardly extending portion and are in alinement with the front slots within said forwardly extending portion, vertically movable type-carrying rods, type members carried thereby and positioned by the rear slots in the vertical portion, and oscillating hammers positioned by the front slots in the forwardly extending portion, said plate having at its upward end, a forwardly extending portion into which 70 the rear slots extend. 60

7. In a mechanism of the character described, the combination of a shaft, oscillating hammers mounted thereon and loosely surrounding said shaft and having a narrow 75 portion engaging therewith and spacing rings separate from said hammers and surrounding said shaft between said hammers and a guide plate having slots for guiding the said hammers at points removed from 80 said shaft.

8. In a mechanism of the character described, the combination of a shaft, oscillating sheet metal hammers each of uniform thickness throughout mounted thereon and 85 loosely surrounding said shaft and spacing rings separate from said hammers and surrounding said shaft between said hammers and a guide plate having slots for guiding the said hammers at points near the heads of 90 said hammers.

CHARLES WALES.
